(57) **CLAIM**

The ornamental design for a wallet, as shown and described.

DESCRIPTION

FIG. 1 is perspective view of a first embodiment of the

wallet in a folded configuration showing our new design; FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a perspective view thereof in an open configuration with a broken line representation of the keys and card slots forming no part of the claimed design;

FIG. 8 is a front elevational view thereof;

FIG. 9 is a top plan view thereof;

FIG. 10 is a bottom plan view thereof;

FIG. 11 is a left side elevational view thereof;

FIG. 12 is a rear elevational view thereof;

FIG. 13 is a right side elevational view thereof;

FIG. 14 is a perspective view thereof in the open configuration with an inside flap open with a broken line representation of the card slots forming no part of the claimed design;

FIG. 15 is a front elevational view thereof;

FIG. 16 is a top plan view thereof;

FIG. 17 is a bottom plan view thereof;

FIG. 18 is a left side elevational view thereof;

FIG. 19 is a right side elevational view thereof;

FIG. 20 is a perspective view of a second embodiment of the wallet in the open configuration with a broken line representation of a connector and speaker for the wallet forming no part of the claimed design;

FIG. 21 is a front elevational view thereof;

FIG. 22 is a top plan view thereof; and,

FIG. 23 is a left side elevational view thereof.

The exterior surface of the second embodiment of the wallet is not shown in the drawings or described in the specification and is understood to form no part of this embodiment of the claimed design.
